UNITED STATES PATENT OFFICE.

WILLIAM H. POTTER, OF PHILADELPHIA, PENNSYLVANIA.

HEAD-HOOP DIE.

No. 887,516.

Specification of Letters Patent.

Patented May 12, 1908.

Application filed May 5, 1906. Serial No. 315,347.

To all whom it may concern:

Be it known that I, WILLIAM H. POTTER, a citizen of the United States, residing at Philadelphia, county of Philadelphia, and 5 State of Pennsylvania, have invented a certain new and useful Improvement in Head-Hoop Dies, of which the following is a specification.

My invention relates to a new and useful 10 improvement in dies for driving and setting the head hoop of barrels and kegs to be used in connection with hoop driving machines, and has for its object to so construct a die of this description that it may be readily attached to the driving arms of an ordinary 15 hoop driving machine without interfering with the present method of driving the second hoop into place but will also adapt the machine for driving home the head hoop.

With these ends in view, this invention consists in the details of construction and combination of elements hereinafter set forth and then specifically designated by the claims.

In order that those skilled in the art to 25 which this invention appertains may understand how to make and use the same, I will describe its construction in detail, referring by letter to the accompanying drawing forming a part of this specification, in which—

Figure 1 is a side view of an ordinary shoe 30 for driving the second hoop upon the barrel or keg showing my improved die in connection therewith for driving the head hoop. Fig. 2, a bottom view of Fig. 1. Fig. 3, a detail view showing the arms of a driving machine with my improved dies attached thereto. Fig. 4, a section of my improved die 35 clearly illustrating the groove around its edges for engaging the head hoop.

Referring to these drawings A represents my improved driving shoe having the corrugated surface B, and D is a lip formed upon this shoe which determines the distance to which the head hoop is driven upon the barrel 40 by coming in contact with the chime of the barrel, thus acting as a gage so as to limit the downward movement of the arms and drive each hoop to the same distance from the chime of the barrel.

C represents the lower edge of the shoe and the surface B furnishes protection to the head hoop in the operation of driving.

E represents the ordinary die for driving the quarter hoop and bilge hoop which is placed against the bottom of the arms of the 55 driving machine, and my improved driving shoe is placed beneath this die, both being secured to the arm by suitable bolt. The die E is made in general shape a square having each of its sides curved inward, these 60 curves being intended to coincide with the curvature of the hoop, and in the bottom face of the die along each of these edges is formed a groove F so as to produce a sharp edged lip for engagement with the top edge 65 of the hoop to be driven.

In practice one of my improved driving shoes having been secured to the lower end of each of the driving arms G the head hoop is set upon the barrel and driven home by the 70 shoe being moved downward by the arms, and when this hoop has been properly driven the arms are moved downward to the bilge hoop which is driven home by the die E and are thence moved upward to the quarter 75 hoop which is driven home in the same manner as the bilge hoop with die E. As the head hoop is driven home the surface B serves as a guide upon the sides of the barrel.

As before stated the dies E are curved inward so that it may be turned upon its axis, and either of these edges utilized for driving the hoops, or where various sized barrels or kegs are to be operated upon the curves in 85 the sides of the die E may be of different radii so as to adapt it for use upon these various sized barrels and kegs.

By the use of my improvement at least half the labor in driving hoops upon a barrel 90 is saved by the fact that the barrel does not have to be removed from the machine when the head hoop is placed, but remains in the same machine until the quarter hoop and bilge hoop are also placed, and this is of 95 great advantage in the trade, producing better work and saving much time and labor. My improved shoe is also adapted for driving wooden hoops from the fact that the lip D is of sufficient width to engage the upper edge 100 of the hoop without cutting into the same. It is to be noted that if desired the die E may be dispensed with and the shoe used independent thereof.

Having thus fully described my invention, what I claim as new and useful, is—

In combination with a hoop driving arm and the hoop driving plate or die, of a shoe secured to said arm below said die or plate 5 and providing a further hoop driving surface other than that of said die or plate by which a head hoop may be driven into place.

In testimony whereof, I have hereunto affixed my signature in the presence of two 10 subscribing witnesses.

WILLIAM H. POTTER.
